UNITED STATES PATENT OFFICE.

WLADYSLAW DOBROWOLSKI, OF PITTSBURGH, PENNSYLVANIA.

CIGAR, CIGARETTE, AND MATCH DISPENSER.

1,144,821.

Specification of Letters Patent. Patented June 29, 1915.

Application filed December 15, 1914. Serial No. 877,382.

To all whom it may concern:

Be it known that I, WLADYSLAW DOBROWOLSKI, subject of the Emperor of Austria-Hungary, residing at Pittsburgh, in the 5 county of Allegheny and State of Pennsylvania, have invented certain new and useful Improvements in Cigar, Cigarette, and Match Dispensers, of which the following is a specification.

10 This invention relates to certain new and useful improvements in cigar, cigarette and match dispensers.

The primary object of this invention is to provide a device which is both ornamental 15 and useful and especially adapted for use upon a desk or counter for containing and dispensing cigars, and cigarettes as well as matches for lighting the same.

A further object is to provide a container 20 for cigars and cigarettes, which is normally closed and adapted to be readily actuated for dispensing one of the contained articles, such operation automatically effecting the opening of a match receptacle.

25 A still further object is to provide a serviceable storage casing for cigars or cigarettes which is bodily movable for individually dispensing the contained articles from the top thereof, the movement of the casing 30 automatically releasing the retaining catch of a spring opened match drawer slidably positioned in a base upon which the casing is mounted.

With these general objects in view and 35 others that will appear as the nature of the invention is better understood, the same consists in the novel combination and arrangement of parts hereinafter more fully described, illustrated in the accompanying 40 drawings and set forth in the appended claims.

In the drawings forming a part of this application and in which like-designating characters refer to corresponding parts 45 throughout the several views, Figure 1 is a perspective view of the device. Fig. 2 is a vertical longitudinal sectional view thereof. Fig. 3 is a vertical transverse sectional view of the device taken upon a plane adjacent 50 one end of the casing. Fig. 4 is an inverted perspective view of a section of the foundation base of the device showing a chamber for the match drawer with the catch mechanism for the drawer, the bottom plate being 55 removed. Fig. 5 is a perspective view of the

match drawer detached, and Fig. 6 is a perspective view of the casing carried trip detached and designed for engaging the match drawer catch.

Referring more in detail to the drawings, 60 it will be noted that the casing 10 which is designed for storing either cigars or cigarettes desired within the inner chamber 11 thereof is made in the form of an artistic representation of a house or cabin, being 65 normally seated upon a solid foundation or base 12 which represents the lot, while steps 13 lead to the top 14 of the foundation which represents a yard and has a border fence 15. At one corner of the yard a well 16 is positioned forming an open top receptacle 17 70 which is serviceable as an ash tray or receptacle, while a representation in miniature of a water drawing device 18 is provided for the well having a suspended bucket 19. 75

The chamber 11 has opposite inclined walls 20 whereby the contents thereof tends to position itself centrally of the bottom of the chamber, while a rectangular post 21 rigidly mounted upon the foundation 12 extends through a central longitudinal slot 22 in the bottom of the casing, and also through a similar slot 23 in alignment therewith through the top of the casing, the casing being slidably mounted for vertical movement 80 upon the said post. Transverse bars 24 are carried by the casing traversing the bottom slot 22 thereof and are slidably received in vertical longitudinal slots 25 of the said post, the said slots extending substantially 85 the same height as the ridge 26 of the casing roof. Opposite chimneys 27 are provided at the top of the post 21 and in central alignment with the said slots 25 and are provided with horizontally aligning top grooves 28 90 adapted for receiving a single cigar or cigarette therein when the casing 10 is elevated to the limit of its movement with the bars 24 positioned at the tops of the slots 25 at which time the grooves 28 will be in 95 alignment with the upper inner open end of the bottom slot 22, it being noted that the chimneys 27 are all substantially the same height as the height of the slot 22.

A bottom chamber 29 is provided in the 100 foundation 12 and is provided with a bottom plate 30 secured to the bottom of the foundation, while the said chamber has an outer open side 31 for allowing a match drawer 32 to slide outwardly and inwardly 105 110

of the chamber 29 within which the said drawer is positioned. A strip 33 having projecting ends is provided upon the bottom of the drawer at one end thereof and has its said ends projecting within the opposite elongated notches 34 of the said foundation and over which notches and strip and base plate 30 is secured thus limiting the length of travel of the drawer. An opening 38 circular in cross section extends inwardly of the foundation 12 and opens at the inner end of the chamber 29, the said opening being designed to accommodate a rod 35 slideable therein and which is centrally carried by the rear wall 36 of the drawer, while a helical spring 37 encircles the rod 35 and is seated within the said opening 38 and has its outer end resiliently engaging the drawer wall 36 whereby the drawer is normally outwardly influenced by the expanding tendency of the said spring. A slightly resilient catch or hook 39 is secured to the foundation at the rear and top of the chamber 29 and normally depends into the path of travel of a catch plate 40 projecting upwardly from the said drawer wall 36. By this provision, it will be seen that when the drawer 32 is forced inwardly against the action of the spring 37 to its closed position the catch hook 39 automatically engages the plate 40 for retaining the drawer so positioned.

A catch releasing device is carried by the foundation consisting of a rocker arm 41 which is of right-angle shape and is pivoted to a post 42 within the chamber 29. An operating lever 43 has its inner end pivoted to one end of the arm 41 while the opposite free end 44 of the said arm normally rests engaging beneath the catch hook 39. The outer end of the rod 43 projects outwardly of the foundation 12 and is provided with a finger plate 45, a contraction spring 46 encircling the rod 43 normally holding the said rod projected.

A trip 47 of the form illustrated in Fig. 6 is secured to the bottom of the casing 10 and has a triangular lower end 48 which extends beneath and in contact with the catch 39 when the casing is normally positioned seated upon the foundation 12.

From this detailed description of the invention, the complete operation of the device will be at once apparent. Cigars or cigarettes being provided in the chamber casing 11, the casing is manually elevated until one of the articles contained therein rests within the grooves 28 when the casing is lowered to its normal position with the chimneys 27 extending above the gable portions of the casing and with the article mounted upon the chimneys where it may be readily removed. The trip 47 is normally positioned engaging the catch 39 as illustrated in Fig. 3, and the elevating of the

casing brings the upper inclined side 49 of the trip head 48 against the catch and thereby elevates the catch simultaneously releasing the same from the plate 40 upon the dispensing movement of the casing, and the 70 spring 37 which is under compression, being thus released forces the match drawer to its open position. It will be evident that whenever it is desired to open the match drawer without removing an article from the casing, the plate 45 may be depressed for rocking the arm 41 and moving upwardly the arm end 44 and the catch 39 for releasing the drawer plate 40.

It will thus be seen that a serviceable desk 80 or counter ornament is provided, the external appearance of which will not disclose the nature of the device, but which at the same time is serviceable in holding and dispensing both cigars or cigarettes as well as 85 matches.

While the form of the invention shown and described is what is believed to be the preferred embodiment thereof, it is nevertheless to be understood that minor changes 90 may be made without departing from the spirit and scope of the invention as claimed.

What I claim as new is:—

1. A device of the class described comprising in combination with a shiftable dispenser, a foundation upon which said dispenser is normally mounted, a drawer slidably carried by said foundation, an expulsion spring for the said drawer, a retaining catch for said drawer, and a releasing trip 100 for the said catch carried by the said dispenser and operatively actuated upon the operation of said dispenser.

2. A device of the class described comprising a foundation having an edge opening chamber therein, an inwardly projecting opening leading from the said chamber, a drawer slidably mounted within said chamber, a rod carried by the inner wall of said drawer and slidably positioned within the said opening, a normally tensioned expansion spring encircling the said rod and having one end seated within the said opening and the other end engaging the said drawer wall, a catch hook carried by the foundation and normally engaging the said drawer wall when the drawer is in its closed position, and a vertically movable triangular trip having its path of movement in the plane of the said catch hook.

3. A device of the class described comprising a foundation having an edge opening chamber therein, an inwardly projecting opening leading from the said chamber, a drawer slidably mounted within said chamber, a rod carried by the inner wall of said drawer and slidably positioned within the said opening, a normally tensioned expansion spring encircling the said rod and having one end seated within the said open-

ing and the other end engaging the said drawer wall, a catch hook carried by the foundation and normally engaging the said drawer wall when the drawer is in its closed position, a rocker arm pivoted within said chamber and having one end engaging the said catch hook, and a normally resilient projecting operating rod pivotally connect-

ed to the other end of said arm and extending exteriorly of the said foundation. 10

In testimony whereof I affix my signature in presence of two witnesses.

WLADYSLAW DOBROWOLSKI.
